(57) **CLAIM**

The ornamental design for a file folder with secured front cover, as shown and described.

DESCRIPTION

FIG. 1 is a front perspective view of the expanded file folder with secured front cover in the closed position;

FIG. 2 is a front perspective view of the expanded file folder with secured front cover in the open position;

FIG. 3 is a front plan view of the expanded file folder with secured front cover of FIG. 1;

FIG. 4 is a back plan view of the expanded file folder with secured front cover of FIG. 1;

FIG. 5 is a left side elevational view of the expanded file folder with secured front cover of FIG. 1;

FIG. 6 is a right side elevational view of the expanded file folder with secured front cover of FIG. 1;

FIG. 7 is a top plan view of the expanded file folder with secured front cover of FIG. 1;

FIG. 8 is a bottom plan view of the expanded file folder with secured front cover of FIG. 1;

FIG. 9 is a front plan view of the file folder with secured front cover of FIG. 1 in unexpanded form.

The broken lines shown in FIGS. 1, 2, 5, 6, 7, and 9 represent fold lines and are part of the claimed design.
